(57) **CLAIM**

The ornamental design of a wheel-arch protector with cladding, substantially as shown and described.

DESCRIPTION

FIG. 1 is a front, perspective view of a wheel-arch protector with cladding in accordance with the present invention; FIG. 2 is a front view of the design shown in FIG. 1; FIG. 3 is a rear view thereof; FIG. 4 is a rear, perspective view thereof; FIG. 5 is a left-side view thereof; FIG. 6 is a right-side view thereof; FIG. 7 is a top view thereof; and, FIG. 8 is a bottom view thereof.

One stippled area is separated from areas having line shading to show contrasting surfaces.

The features shown in broken lines are directed to environmental structure and do not form part of the claimed design.
